(74) Attorney, Agent, or Firm—Foley & Lardner

(57) **CLAIM**

I claim the ornamental design for the kneeling disk, as shown and described.

DESCRIPTION

FIG. 1 is a perspective of a kneeling disk;

FIG. 2 is a top view of the kneeling disk shown in FIG. 1; FIG. 3 is a bottom view of the kneeling disk shown in FIG. 1;

FIG. 4 is a front view of the kneeling disk shown in FIG. 1; FIG. 5 is a right side view of the kneeling disk shown in FIG. 1;

FIG. 6 is a back view of the kneeling disk shown in FIG. 1; and,

FIG. 7 is a left side view of the kneeling disk shown in FIG. 1.

The broken lines in FIGS. 1-7 showing portions of the upper edge of the kneeling disk and portions of a soft cushion are for illustrative purposes only and form no part of the claimed design.
